UNITED STATES PATENT OFFICE.

CHARLES S. FRANKEL, OF NEW YORK, N. Y., ASSIGNOR TO FRANKEL CONNECTOR CO., INC., A CORPORATION OF NEW YORK.

CABLE TAP.

Application filed December 8, 1923. Serial No. 679,452.

To all whom it may concern:

Be it known that I, CHARLES S. FRANKEL, residing at New York, in the county and State of New York, a citizen of the United States, have invented certain new and useful Improvements in Cable Taps, of which the following is a specification.

The object of my invention is to provide an improved form of "cable tap". It may be explained that a cable tap is a device used to connect a branch wire, rod, or bleeder to a main wire, rod, or bleeder; it does not splice the main, but simply clamps onto it.

More specifically, the object is to provide a cable tap having improved means for more effectually clamping the bare end of the branch conductor in the compression sleeve of the cable tap.

With these objects in view, and others appearing as the specification proceeds and the nature of the invention is more fully disclosed, the cable tap of my invention comprises the novel construction, combination and co-operative arrangement of structural parts, as will be more fully hereinafter described, as summarized in the claims, and as illustrated in the accompanying drawing, forming part of the specification.

Referring briefly to the drawing, in which like reference-characters identify corresponding structural parts throughout the several views:

Figure 1 is a view in elevation of a cable tap constructed in accordance with my invention;

Figure 2 is a vertical sectional view, taken on the plane of the section line 2—2, Fig. 1, looking in the direction of the arrows indicated thereon;

Figure 3 is a horizontal sectional view, taken on the plane of the section line 3—3, Fig. 2, looking in the direction of the arrows indicated thereon; and

Figure 4 is a detached detail view, in plan, of the coupling member, hereinafter described in detail.

Figure 5 is a detached, detail view, in side elevation, partly in section, of a modified form of compression-sleeve.

Referring, now, in detail to the drawing:

The cable tap exemplified in the drawing, and capable of carrying out the underlying principles of my invention, includes the main connector body 1 having a threaded

socket 2 and a lateral, offset, upward-projecting neck 3 carrying, laterally, the angularly projecting bridge or flange 4, which, for the sake of lightness, is provided with the cut away portions 5 and 6. While I have shown the main connector body 1 and the bridge member 4 as being integral, it is to be understood that they may be separate pieces, suitably secured together, as is obvious.

Co-operating with the bridge member 4 to secure the cable tap to a main cable A is a coupling member 7, recessed at 8 and 9 to provide four ears 10 apertured to provide bolt-openings 11, which, when the coupling member is disposed in operative position relative to the bridge-member 4 (as shown in Figs. 1 and 2) are alined with corresponding bolt-openings in the latter, whereby threaded bolts 12 may be projected through 75 said alined openings, and nuts 13 screwed on said bolts. The coupling-member 7 carries, on one face thereof, rectilinear projections 7', against which the heads 12' of the bolts 12 abut, so that turning of the 80 bolts is prevented.

The bridge-member 4 and the coupling member 7 are provided, on opposing faces, with complemental recesses 14, machined to fit the main cable A, in which recesses 85 the cable reposes in the operative position of the cable tap, as shown in the drawing.

Adapted to be screwed into the threaded socket 2 of the connector body 1 is the lateral, threaded portion 15 of a compression-sleeve member 16, which is provided, between its ends and preferably adjacent one end of the threads on the threaded portion 15, with a circumferential enlargement 17, having hexagonal faces for engagement by 95 a wrench. A jam or lock nut 18, carried by the threaded portion 15 of the compression-sleeve member 16, is screwed up against the end of the connector body 1.

The compression-sleeve member 16 is provided with a longitudinally-extending recess or socket 19; and the wall of this socket, from the outer end thereof to a point some distance short of the inner end, is provided with a plurality of longitudinally-extending, equidistantly spaced slits 20, whereby a plurality of resilient fingers is formed.

Preferably, the inner surface of the wall of the socket 19, extending throughout substantially the entire length of said slits 20, 110

is provided with grooves 21, for the purpose presently appearing; or, as shown in Fig. 5, these grooves may be omitted.

The compression-sleeve member 16, extending from the inner end of the slits 20 to the enlargement 17, is screw-threaded exteriorly, as shown at 22, for engagement by a compression nut 23, which is internally threaded toward one end thereof, as shown at 24, and exteriorly threaded toward the other end thereof, as shown at 25, and which is also provided, internally, toward one end thereof, with an annular, inclined or tapering shoulder 26, adapted, when the nut is screwed up on the compression-sleeve member 16, to bear against a complementary inclined or tapering face on said sleeve member, as clearly shown in Fig. 2, thereby compressing the resilient spring fingers of the sleeve-member 16 and causing them to forcibly engage or bind against the branch conductor cable B, which is inserted in the socket 19, and hold the same against accidental displacement.

25 The compression-sleeve member 16 is provided with a tapering extremity 27, which, when a second compression nut 28 is screwed upon the threaded portion 25 of the compression-sleeve member 16, is engaged by the complementary tapering internal shoulder 29 of said nut, thereby further to compress the spring fingers of the compression-sleeve member 16 and cause them to more tightly bind against the conductor cable B.

35 It will be obvious, of course, that, instead of a threaded connection between the compression-sleeve member 16 and the main conductor body 1 (as previously described and as shown in the drawing), said main conductor-body and the compression sleeve may be made integral.

The operation of the device is obvious, but may be briefly stated to be as follows: When it is desired to assemble the cable-tap of my invention in operative relation to a main cable A and the branch cable B, the main connector-body 1 is disposed so that the bridge-member 4 lies over the cable A, with the cable resting in the groove 14 of the bridge-member. Thereupon, the coupling-member 7 is disposed beneath the bridge-member 4, so that the cable A also rests in the groove 14 of the coupling-member; and the bolts 12 are inserted in the bolt-openings 55 11 of the bridge-member 4 and the coupling-member 7, and the nuts 13 screwed up tightly, whereupon the cable A is securely held by said bridge-member and coupling member, with the main connector body 1 suspended in a vertical position. The compression-sleeve member 16 is now screwed into the socket 2 of the connector body 1, and the lock-nut 18 adjusted. Then, one end of the branch cable B is inserted in the socket 19, and the compression-nut 23 adjusted on the

compression-sleeve member 16 until the tapering shoulder 26 of the nut bears forcibly against the complementary inclined or tapering face on the exterior of the compression-sleeve 16, thereby compressing the fingers of the compression sleeve and binding them tightly against the cable B. As the cable is thus tightly grasped, portions thereof will be forced into the grooves 21 internally of the compression-sleeve 16, these grooves thereby functioning in increasing the resistance to slipping or pulling out of the cable B from the socket 19. Finally, the end compression nut 28 is screwed on the end of the compression-nut 23 until the tapering shoulder 29 thereof bears forcibly against the tapering extremity 27 of the compression-fingers of the compression-sleeve 16, thereby forcing the extremities of said fingers inward to cause the same to bind still more tightly against the cable B. The device thus presents triple clamping means, namely, (1) the compression-nut 16, (2) the grooves 21, and (3) the end compression nut 28, all coordinated and co-operating as described.

Having thus fully described my invention, what I claim as new and desire to secure by Letters-Patent of the United States is:

1. A cable tap comprising a main connector body, a compression-sleeve member carried by said body and having resilient terminal-fingers, a main compression-member engageable with said fingers to force them into clamping relation with a branch cable, and an auxiliary compression-member engageable with the extremities of said fingers to force them into clamping relation with said branch cable.

2. A cable tap comprising a main connector body, a compression-sleeve member carried by said body and having resilient terminal-fingers, a main compression nut adapted to be screwed on said compression sleeve member and to force said fingers into clamping relation with a branch cable, and an auxiliary compression-nut adapted to be screwed on said main compression-nut and engageable with the extremities of said fingers to force them into still tighter clamping relation with said branch cable.

3. A cable tap comprising a main connector body, a compression-sleeve member screwed into said body and having resilient terminal-fingers, a main compression-member engageable with said fingers to force them into clamping relation with a branch cable, and an auxiliary compression-member engageable with the extremities of said fingers to force them into still tighter clamping relation with said cable.

4. A cable tap comprising a main connector body, a compression-sleeve screwed into said body and having resilient terminal-fingers, a lock nut carried by said compres-

- sion-sleeve and adapted to be screwed up against said connector body, a main compression-member engageable with said fingers to force them into clamping relation with a branch cable, and an auxiliary compression member engageable with the extremities of said fingers to force them into still tighter clamping relation with said cable.
10. 5. A cable tap comprising a main connector body, a compression-sleeve member carried by said body and having resilient
- terminal fingers, said fingers, intermediate their ends, having a circumferential tapered face, the extremities of said fingers being 15 also tapered, a main compression-nut screwed on said compression-sleeve member and having a tapering internal shoulder engageable with said circumferential tapered face intermediate the ends of said fingers, and an auxiliary compression nut likewise having an internal tapering shoulder engageable with the tapered extremities of said fingers.

CHARLES S. FRANKEL.
